UNITED STATES PATENT OFFICE.

EARLE M. WOODEN, OF NEW YORK, N. Y., ASSIGNOR TO THE PERFECTOGRAPH MANUFACTURING COMPANY, OF NEW YORK, N. Y., A CORPORATION OF DELAWARE.

MAGAZINE FOR MOVING-PICTURE FILMS.

1,202,346.

Specification of Letters Patent. Patented Oct. 24, 1916.

Application filed February 15, 1915. Serial No. 3,172.

To all whom it may concern:

Be it known that I, EARLE M. WOODEN, a citizen of the United States, and a resident of the borough of Manhattan of the city of New York, in the State of New York, have invented certain new and useful Improvements in Magazines for Moving-Picture Films, for which I am about to make application, reference being had to 10 the accompanying drawings, which form a part hereof.

In accordance with present day practice, a housing for the reels of moving picture films is mounted on the casing of the machine and the film is passed from the reel housing down through a slot in the casing of the machine and through the feeding mechanism to the winding-on spool which may be located at any convenient point. 15 After the film has been run through the machine, an empty spool is left in the reel housing and this empty spool must be removed from the housing by the operator and a fresh reel then inserted, whereupon the 20 fresh film can be fed through the machine and the exhibition repeated in the usual manner. Since the fire underwriters require the film to be inclosed, the removal of the empty spool and the substitution and setting 25 of a fresh film entails the opening and subsequent closing of a suitable door in the film housing and other manipulations which require an appreciable period of time, depending somewhat on the skill of the operator, 30 and cause an annoying interval between exhibitions.

It is the object of this invention to reduce the time required for the placing of fresh reels to a minimum and to remove, as 40 far as possible, the personal factor which hitherto has been involved where the length of the interval between exhibitions has depended on the skill of the operator. In accordance with the invention a magazine, as 45 such, is provided in place of the usual film housing and this magazine is formed with a plurality of compartments, in each of which may be mounted, in readiness for use, a fresh film, and that, too, regardless of 50 whether the other compartments contain films or not. In the illustrated embodiment, for instance, a magazine is shown in which there are two compartments, one of 55 which may be charged with a fresh film during the exhibition of the film in the other

compartment. As soon as the exhibited film is run through the machine, the magazine may be moved quickly to bring the charged compartment with the fresh film into position for exhibition. The empty spool in the other compartment is then replaced at the 60 leisure of the operator by a fresh film and so the exhibition continues with very slight delay between films.

Reference is now to be had to the accompanying drawings for a detailed description of the preferred embodiment of the invention, in which—

Figure 1 is a view, partly in side elevation and partly in section, of a magazine 70 embodying the invention, mounted on the casing of a moving picture machine. Fig. 2 is a view in section, taken on the plane indicated by the line 2—2 of Fig. 1 and looking in the direction of the arrows, a fragment of the casing of the moving picture machine being indicated. Fig. 3 is a view in plan of the magazine shown in Fig. 1, certain details of construction being indicated in dotted lines.

In the top wall *a* of the appropriate portion of the casing of a moving picture machine, indicated generally at *a'*, is formed a slot *a*, through which may be run the film *b* and in juxtaposition to this slot is fastened a 85 suitable base *c* formed with a vertically disposed bearing stud *c'* over which may be readily placed a hollow supporting cap *d* for the improved magazine *d'*, the connection between the cap *d* and the stud *c'* being 90 such as to permit the magazine to be readily rotated about the vertical axis of the cap.

The housing *d'* may be of any desired form, but in the illustrated embodiment is shown as substantially cylindrical and as 95 formed with two non-communicating compartments *d*² and *d*³, separated by a vertically disposed partition plate *d*⁴ secured at about the mid section of the housing. In the partition plate *d*⁴ may be mounted oppositely extending supporting shafts *e*, the axes of 100 which are preferably co-incident with the axis of the housing *d'*. Each magazine chamber *d*², *d*³ is formed with a door *d*⁵ on which may be fixed a convenient latch *d*⁶, 105 the form of which may be such as to facilitate the opening and closing of the door.

From the description, it will be evident that in the use of the improved magazine, the operator will open one of the doors *d*⁵ and slip 110

a fresh reel into one of the compartments, say d^3 , onto the supporting shaft e and then feed the film b down through a slot d^7 formed at the bottom of each compartment 5 d^2 , d^3 , and the slot a^2 in the housing a , in accordance with the usual method. The door d^5 is then latched and the exhibition commenced. During the exhibition a fresh reel may be placed in the other compartment d^2 in the manner described in connection 10 with the placing of the reel in the compartment d^3 . As soon as the film b has been run off the spool in the compartment d^3 , the operator quickly rotates the magazine d' about its pivotal support c' until the slot d^7 in the base of the chamber d^2 comes into proper position with respect to the slot a^2 , whereupon the fresh film is fed down through the two slots in the usual manner. 15

20 During the exhibition of this film the empty spool in the other chamber may be removed and replaced by a fresh reel, in readiness for immediate exhibition.

If desired the magazine d' may be provided 25 with more than two chambers as the invention is not to be limited to the shape of the magazine or to the number of compartments therein; and the mechanical devices for supporting it in such position as to 30 permit fresh films to be brought successively and by simple manipulation by the operator into position for exhibition, may vary widely.

The essence of the invention lies in the facility for bringing reels which are mounted in readiness for exhibition, successively into position for display of the respective films. It is to be noted also that means may be employed for stopping the magazine automatically in the appropriate positions for exhibition of the films in the respective chambers. 35 40

I claim as my invention:

A unitary magazine for films of moving pictures comprising a substantially cylindrical integral housing divided interiorly into two compartments, shafts independent of the machine to support a reel in each compartment, a slot in the bottom wall of each compartment through which the film may be run, a bearing post carried on the casing of the moving picture machine with which coöperates a socket formed in the housing of the magazine, whereby the magazine may be removably mounted on the post and rotated about a vertical axis to bring the slot of either compartment into registry with a corresponding slot in the casing of the moving picture machine to permit the film to be drawn through said slots and projected. 45 50 55 60

This specification signed and witnessed this 21st day of December, A. D. 1914.

EARLE M. WOODEN.
